REVERSIBLE REED FOR WIND INSTRUMENTS

Jules Miller, Atlantic City, N. J.

Application December 24, 1947, Serial No. 793,577

6 Claims. (Cl. 84—383)

2

Fig. 1 is a side view showing the mouth-piece, reed, and clamp or ligature for holding the reed in position.

Fig. 2 is a sectional view taken on line 2—2 of Fig. 1.

Fig. 3 is a side view of the reed showing how it appears after several hours playing, and

Fig. 4 is a similar view showing the reed reversed and ready to be placed on the mouth-piece.

Referring now more particularly to the several views, and for the moment to Figs 1 and 2, there is shown the removable mouth-piece 1 of a wind musical instrument with the reed 2 clamped on the flat lay 3 of the mouth-piece 1 and the clamp 4 for tightly holding the reed 2 in position.

It will be understood that I may use any form of clamp or ring for holding the reed 2 in position.

20 The mouth-piece 1 as illustrated is of the conventional type and has the usual tapered wall 5 and an entrance opening 6 that terminates as at 7. The mouth-piece 1 is curved slightly downwardly as at 8 to allow for the vibrations of the reed 2.

Referring now more particularly to the gist of the invention, that is, the reversible reed 2, it will be seen that it tapers from its proximal end 9 to its distal end 10, and is substantially two to 30 five thousandths of an inch (2/1000 to 5/1000") thick at its proximal end 9, and may be substantially five thirty-seconds of an inch (5/32") at its distal end 10.

The upper surface 11 is identical with its under-surface 12, so that when clamped to the mouth-piece 1, regardless of which surface, that is 11 or 12, is uppermost, the action will be exactly the same.

35 The reed 2 may be of several widths and the narrower size may be used for clarinets while the wider ones are for use for the base, tenor and alto, and other saxophones.

By forming the reed 2 with the upper and lower surfaces 11 and 12 identical, it will be seen that 40 the reed 2 may be clamped to the mouth-piece 1 with either surface uppermost. This provides a great advantage over the reeds now in service, as after a reed is used for several hours on a clarinet, the pressure from the lips of the player and the moisture from the lips will cause the reed to bend downwardly towards the mouth-piece 1 at its proximal end 9 and will curve to such an extent that in the ordinary form of reed it has to be discarded, and a new one substituted.

45 However, by making the reed reversible, that

1 My invention relates to new and useful improvements in reeds for wind instruments, such as the clarinet, saxophone and the like; and has for an object to provide a reed that will give from two to ten times the service of the conventional type.

One of the principal objects of the invention is to provide a reed that is reversible so that after a few hours of use by the player the reed may be removed, and, instead of being discarded on account of being warped or bent towards the mouthpiece, may be reversed, that is, turned over and placed back on the lay of the mouth-piece; and, although it will take slightly more pressure by the lips of the player, it will operate well and will soon curl or bend back to its normal position and still farther to an extreme, when it may again be reversed to its first position and used until again necessary to reverse it.

Thus not only may the life of the reed be doubled, but it may be reversed many times before it is found necessary to discard the same.

Another object of the invention is to make this reversible reed having two like or exactly opposite faces so that the reed may be clamped with either face downwardly and then after becoming bent, rather than discarding it, it may be reversed and continued in use as above mentioned.

Still another principal object of the invention is to provide a reed with a slight excess of material on its opposite faces near its proximal end to add slight weight to the proximal or vibrating end of the reed to thus control or slightly dampen the vibrations.

Still another object of the invention is to provide a means for controlling the vibrations of the reed, but so construct the remainder of the reed that it may quickly be reversed in position so that after it curls or bends in one direction, as towards the mouth-piece, it may be reversed so that the reed will straighten out and again bend towards the mouth-piece.

Still another object of the invention is to make a reed especially from reed cane with the two like faces and with the small protuberance of excess material near the proximal end so that an experienced player may produce more varied notes on the instrument.

With these and other objects in view the invention consists in certain new and novel arrangements as will hereinafter be more fully described and pointed out in the claims.

Referring now to the drawings, showing a preferred embodiment,

is, with both surfaces the same, as in the present instance, the reed may be used until such time as it curves or bends or warps downwardly, as shown in Fig. 3, and when it would otherwise become non-useful, the clamp 4 is removed from the mouth-piece 1 and the reed 2 simply reversed and again placed in position and held by the clamp 4; and, although it may take slightly more pressure from the lips at the start, it will soon tend to bend to its normal position and then again downwardly to an abnormal position, whence it may again be removed, reversed and placed back in the instrument.

Therefore, a reed when used in this manner, will give from two to ten times the service of the conventional or ordinary type of reed now in use.

Also, as shown in the several views, I have further improved the ordinary reed by providing a means for affecting the notes in the lower register. Furthermore, I have found that the excess material near the proximal end will also favorably affect the notes in the higher register as it adds strength to the reed which is held with what might be termed the shorter bite in the mouth for notes in the higher register. I have also found that by providing the excess material as shown, it permits a player to obtain variations in the tones that are not possible with the conventional reed.

I produce this varying effect by providing a slight excess of material at the proximal end 9 to thus add a slight additional weight to the vibrating end. When the reed is formed I leave the small convex portion 13 centrally of the reed, that is, centrally transversely of the reed, and spaced a slight distance rearwardly from the proximal end 9 and terminating as at the point 14 which is well forward of the rear wall 7 of the opening in the mouthpiece 1.

This convex additional portion 13 on the upper surface is repeated as at 15 on the under-surface 12 of the reed 2 so that this additional weight of material is the same on both the surfaces and diametrically opposite each other.

These excess materials or protuberances 13 and 15 are elongated in shape and are slightly rounded, as may be seen in the several views.

It will be understood that no two reeds are alike and the vibrations of a reed formed in this manner can even be changed by slightly sandpapering these protuberances 13 and 15, or excess material.

In this way, the balancing or governing weight for grading the reed 2 may be obtained. This excess of material 13 and 15 also, of course, will strengthen the reed 2 somewhat at its proximal end 9. Also, it is within the province of the invention to have the protuberance on just one face of the reed, although I prefer the two, as illustrated.

From the foregoing, it will be seen that I have provided, first, a reed that may be used for a number of times, rather than being discarded

after it becomes slightly warped or bent, so that the life of the reed is many times greater than that of the ordinary reed which has to be discarded after it becomes warped; and, secondly, by providing the slight excess material or weight at the proximal end of the reed, without in any way changing the rear portion of the reed, I can change the vibrations of the reed to produce varied notes, and this additional material may, if desired, be slightly rubbed down with sand-paper or emery cloth to suit the musical or artistic temperament of the individual player.

Finally, the reeds, of course, are preferably made from reed cane; although it is possible that they might be cast from a plastic composition.

Having thus described my invention, what I claim is new and desire to secure by Letters Patent is:

1. A reversible reed for clarinet, saxophone and the like, tapering from its proximal to its distal end and the surface contour of the two faces being identical.

2. A reversible reed for clarinet, saxophone and the like, tapering from substantially three thousandths of an inch ($\frac{3}{1000}$ ") at its proximal end to five thirty-seconds of an inch ($\frac{5}{32}$ ") at its distal end, and the surface contour of the two faces being identical.

3. A reversible reed for clarinet, saxophone and the like, tapering from its proximal to its distal end, the surface contour of the two faces being identical, and a small protuberance of additional material on the opposite faces of the reed near the proximal end and centrally located transversely of the reed to provide a governing effect for the vibrations.

4. A reversible reed for clarinet, saxophone and the like, tapering from its proximal to its distal end, and means near the proximal end of the reed and centrally located transversely of the reed to provide a governing effect for the vibrations.

5. A reversible reed for clarinet, saxophone and the like, having like plane surfaces on its opposite faces with the exception of additional centrally located means provided near the proximal end and terminating short of one-half of the length of the reed to thereby provide a governing effect for the vibrations.

6. A reversible reed for clarinet, saxophone and the like, the opposite surfaces presenting a plane surface with the exception of a small protuberance on one face of the reed and near the proximal end thereof to provide a controlling effect for the vibrations of the reed.
